UNITED STATES PATENT OFFICE.

DAVID J. CARTWRIGHT, OF HULL, MASSACHUSETTS, ASSIGNOR OF ONE-HALF TO WALTER S. WAIT, OF NEWTON, MASSACHUSETTS.

PERCUSSION-FUSE.

SPECIFICATION forming part of Letters Patent No. 767,543, dated August 16, 1904.

Application filed August 19, 1903. Serial No. 170,083. (No model.)

To all whom it may concern:

Be it known that I, DAVID J. CARTWRIGHT, a citizen of the United States, residing at Hull, in the county of Plymouth and State of Massachusetts, have invented certain new and useful Improvements in Percussion-Fuses, of which the following is a specification, reference being had therein to the accompanying drawings.

10 The present invention relates to safety-fuses for explosive projectiles, and has for its object to provide a fuse which may be safely handled or transported and all danger of premature or accidental explosion of the projectile due to 15 shock from rough handling or falling from a considerable height entirely eliminated, and yet secure a fuse which when the projectile is discharged from the gun will by reason of the centrifugal action due to the rapid rotation 20 of the projectile and the transmitted heat incident to discharge of the projectile from the gun be "armed" automatically and with certainty, so that explosion of the projectile will occur upon striking.

25 In the drawings herewith I have illustrated several embodiments of my invention.

In said drawings, Figure 1 is a longitudinal sectional view of a safety-fuse constructed in accordance with my invention. Fig. 2 is a 30 transverse sectional view on line 2 2 of Fig. 1. Fig. 3 is a longitudinal sectional view of a different form of my invention. Fig. 4 is a transverse sectional view on line 4 4 of Fig. 3. Fig. 5 is a view similar to Figs. 1 and 2, 35 showing another form of my invention. Figs. 6 and 7 are detail views of the locking device used in connection with the fuses shown in Figs. 1 and 2. Fig. 8 is a detail view of the locking device used in connection with the fuse 40 shown in Fig. 5.

Referring to the drawings by numerals, like parts being indicated by like numbers in the several views, and referring first to Fig. 1, the numeral 1 denotes a fuse-case of such construction as will adapt it for insertion in a projectile. Said fuse-case is chambered, as shown, and is provided with the ordinary fuse-magazine 2, containing the usual detonating charge and percussion cap or member.

Within said chamber of the fuse-case 1 is a 50 firing-plunger 3, having the usual firing-pin to strike the percussion-cap, said plunger 3 being provided with a groove or recess 4. Said groove or recess in the form of the fuse shown in Fig. 1 registers normally with a 55 groove or recess 5 in the inner wall of the fuse-case. Seated within the groove 5 is a continuous divided annular strip 6, provided with inwardly-projecting lugs 7, which engage the groove or recess 4 in the plunger 3. 60 The said annular strip 6 normally lies in the position shown in Fig. 2 in full lines and in Fig. 6 with its ends lapped upon each other, the diameter of the annular strip 6 when in this position being considerably less than the 65 diameter of the groove or recess 5 in the wall of the fuse-case 1. The said annular strip 6 is made of two strips of metal having unequal coefficients of expansion, so that an annular strip or divided ring sensitive to thermic 70 changes is formed.

It will be apparent that when the parts are in the position shown in Fig. 1 the annular strip 6, with its inwardly-projecting lugs 7, will lock the detonating-plunger in its rearward or safe position and hold it securely 75 against longitudinal movement and that shocks incident to rough handling or dropping of the projectile will not affect the plunger-locking device. When, however, the projectile is discharged from the gun, the rapid rotary motion imparted thereto will cause the annular strip or divided ring 6 to expand under centrifugal action to the position shown 80 in Fig. 7, with its normally lapped ends abutting and with the lugs 7 withdrawn from the groove or recess 4 in the detonating-plunger. Owing to the thermostatic characteristics of the annular strip 6, this expanding action of 85 the strip will be aided by the heat which is generated upon discharge of the projectile from a gun being transmitted to the ring or annular strip, and it will thus be seen that expansion of the annular strip 6 is rendered certain because of both the action of centrifugal force thereon, aided by the thermic effect of transmitted heat, and the fuse, while 90 effectively locked in safe position against all

accidental "arming", will be completely and certainly armed as soon as the projectile is discharged from the gun.

In order to prevent accidental creeping forward of the detonating-plunger 3 during the flight of the projectile, I provide a light spring 8 between the fuse-magazine 2 and the detonating-plunger 3, which spring has sufficient strength to counteract the tendency of the detonating-plunger to creep forward during the flight of the shell, but which will yield readily upon impact or striking of the projectile and permit the detonating-plunger 3 to drive forward, strike the percussion-cap, and ignite the detonating charge.

In Fig. 3 I have shown a construction of fuse differing somewhat from that shown in Fig. 1, although containing the same essential characteristics. In the construction shown in Fig. 3 the detonating-plunger 9 is capable of longitudinal movement within the fuse-case, but is held from rotation by any suitable means—as, for example, by means of a pin 10, projecting into a longitudinal groove or recess 11 in the plunger 9. The said plunger is provided with an elongated firing-pin 12, upon which is mounted a protecting-sleeve 13, said sleeve 13 being connected with the firing-pin 12 by means of a quick-turning screw-thread connection 14. Between the rear ends of the said arming-sleeve 13 and the plunger 9 is placed the thermostatic locking-strip 15, which is identical in construction with the thermostatic locking-strip described in connection with Fig. 1, the lugs 16 of the strip 15 dropping behind the rear end of the sleeve 13 and holding the parts in the position shown in Fig. 3, the rear ends of the sleeve 13 being reduced, as at 17, to give clearance for the locking-lugs 16 of the strip 15 when the said strip has been expanded by centrifugal force and thermic action upon the discharge of the projectile from the gun.

In the construction shown in Fig. 3 it will be apparent that upon discharge of the projectile from a gun the annular strip 15 will expand to the position shown in Fig. 7 and release the detonating-plunger 9 and the sleeve 13 by withdrawing the interposed lugs 16 from between the two parts. In this position the sleeve 13 is free to move rearwardly and arm the detonating-plunger 9, for since the sleeve 13 is free to rotate upon the elongated firing-pin 12 it is apparent that the inertia of the said sleeve 13 will cause it to ride back upon the screw-threaded firing-pin 12 under the action of rotary inertia when the projectile is discharged from a gun. When the sleeve 13 has run back upon its quick-turning screw-thread connection with the firing-pin 12 to the position shown in outline by the dotted lines in Fig. 3, the firing-point 12 will be armed and in position to strike the percussion-cap upon impact of the projectile.

In order to prevent the accidental creeping

forward of the detonating-plunger 9 during the flight of the projectile, to which reference was made in connection with Fig. 1, a similar anticreeping-spring 19 is interposed between the fuse-magazine and the forward end of the sleeve 13, said spring being preferably located within an annular groove or recess formed at the forward end of the sleeve 13, as shown in Fig. 3.

Instead of the type of thermostatic locking device above described I may use the thermostatically-operated locking device shown in Fig. 5, in which the detonating-plunger is provided with a forwardly-projecting firing-pin 20, which supports a ring 21, made of material fusible at comparatively low temperatures, said ring 21 bearing against a nipple 22, projecting rearwardly from the fuse-magazine and serving to hold the detonating-plunger normally in the position shown in Fig. 5. With this construction it is obvious that when the projectile is discharged from the gun the transmitted heat of discharge will attack the easily-fused ring 21 and dissipate it, and the melted material will at once be thrown outwardly to the wall of the fuse-case by centrifugal action induced by the rapidly-rotating projectile and arm the detonating-plunger. The anticreeping-spring 23, similar to those above described, will be interposed between the fuse-magazine and the detonating-plunger to prevent accidental longitudinal movement of the plunger during the flight of the projectile. Said spring is seated at its ends in grooves or recesses 24 and 25, formed, respectively, in the face of the plunger and the rear wall of the fuse-magazine, so that the fused material may be thrown outwardly through the coils of the spring to the fuse-case wall and will not clog or impede the spring 23 so as to hinder the forward movement of the plunger upon impact of the projectile.

While I have shown and described particular constructions of my invention and those the best known to me, I do not wish to be understood as limiting my invention to any of the details of construction shown and described except in so far as I am limited by the terms of the appended claims, for it is apparent that variations of the structures shown and described well within the skill of the mechanician may be made without departing from the spirit of my invention.

What I claim is—

1. A fuse for explosive projectiles comprising a fuse-case; a percussion member; means for detonating said percussion member; and a locking device, comprising two substances mechanically secured together and differently expansible under thermic action, for normally holding said detonating means in safe position, said locking device being adapted to expand and release said detonating means upon firing of the projectile.

2. A fuse for explosive projectiles comprising

ing a fuse-case; a percussion member; means for detonating said percussion member, and a centrifugally-expansible locking device, comprising two substances mechanically secured together and differently expansible under thermic action, for normally holding said detonating means in safe position, said locking device being adapted to expand and release said detonating means upon firing of the projectile.

3. A fuse for explosive projectiles comprising a fuse-case; a percussion member; means for detonating said percussion member; and a normally contracted locking device, composed of two substances differently expansible under thermic action, for holding said detonating means normally in safe position, said locking device being adapted to expand and release said detonating means upon firing of the projectile.

4. A fuse for explosive projectiles comprising a fuse-case; a percussion member, means for detonating said percussion member; and a thermostatic device normally contracted in safe position, and expansible under thermic action upon firing of the projectile to release said detonating means.

5. A fuse for explosive projectiles comprising a fuse-case, a percussion member; means for detonating said percussion member; and a thermostatic device normally contracted to lock said detonating means normally in safe position and expansible under thermic action to release said detonating means, and which, when in expanded condition, is itself locked against contraction.

6. A fuse for explosive projectiles comprising a fuse-case; a percussion member; means for detonating said percussion member; and an annular thermostatic strip, composed of two substances differently expansible by heat, to lock said detonating means normally in safe position, said locking-strip being adapted to expand and release said detonating means upon firing of the projectile.

7. A fuse for explosive projectiles comprising a fuse-case; a percussion member; means for detonating said percussion member; and a divided annular thermostatic strip, composed of two substances differently expansible by heat, to lock said detonating means normally in safe position, said locking-strip being adapted to expand and release said detonating means upon firing of the projectile.

8. A fuse for explosive projectiles comprising a fuse-case; a percussion member; means for detonating said percussion member; and a divided thermostatic ring composed of two substances differently expansible under thermic action and normally contracted to lock said detonating means normally in safe position, the substances most sensitive to heat composing the inside part of said ring, said ring being adapted to expand and release said detonating means upon firing of the projectile.

9. A fuse for explosive projectiles comprising a fuse-case; a percussion member; means for detonating said percussion member; and a divided thermostatic annular strip normally contracted to lock said detonating means in safe position and expansible under thermic action to release said detonating means, and which, when in expanded condition, is itself locked against contraction.

10. A fuse for explosive projectiles comprising a fuse-case; a percussion member; means for detonating said percussion member; and a divided thermostatic annular strip, normally contracted with its ends lapped, to lock said detonating means normally in safe position, and expansible under thermic action to position with its ends abutting to release said detonating means.

11. A fuse for explosive projectiles comprising a fuse-case; a percussion member; a detonating-plunger movable longitudinally within said fuse-case; and an annular thermostatic strip, composed of two substances differently expansible by heat, to lock said longitudinally-movable plunger normally in safe position, said locking-strip being adapted to expand and release said plunger upon firing of the projectile.

12. A fuse for explosive projectiles comprising a fuse-case; a percussion member; a longitudinally-movable detonating-plunger; a protecting-sleeve movable relative to said plunger, and an annular locking device, composed of two substances differently expansible by thermic action, for holding said sleeve normally in safe position, said locking device being adapted to expand and release said plunger upon firing of the projectile.

13. A fuse for explosive projectiles comprising a fuse-case; a percussion member; a longitudinally-movable detonating-plunger; a protecting-sleeve movable relative to said detonating-plunger; and an expandible ring, composed of two substances differently expansible by thermic action, for holding said sleeve normally in safe position, said ring being adapted to expand and release said plunger upon firing of the projectile.

14. A fuse for explosive projectiles comprising a fuse-case; a percussion member; a longitudinally-movable detonating-plunger; a protecting-sleeve movable relative to said plunger; said plunger and sleeve having a screw-threaded connection so as to be adapted to have relative longitudinal movements within said case, by rotary inertia; and means, releasable upon firing of the projectile, for locking said sleeve normally in safe position.

15. A fuse for explosive projectiles, comprising a fuse-case; a percussion member; a detonating-plunger having a screw-threaded portion and longitudinally movable within the fuse-case, but locked against rotary movement relative thereto; a protecting-sleeve having a connection with the threaded por-

tion of said plunger and rotatable within said fuse-case and movable longitudinally relative to said plunger by rotary inertia; and a locking device, releasable upon firing of the projectile, for locking said sleeve normally in safe position.

16. A fuse for explosive projectiles, comprising a fuse-case; a percussion member; a detonating-plunger longitudinally movable within the fuse-case, but locked against rotary movement relative thereto; a protecting-sleeve rotatable within said fuse-case and movable longitudinally relative to said plunger; said plunger and sleeve having a screw-threaded connection so as to have relative longitudinal movements within said case by rotary inertia, and a locking device, sensitive to thermic action, for locking said sleeve normally in safe position.

17. A fuse for explosive projectiles comprising a fuse-case; a percussion member; a non-rotatable longitudinally-movable detonating-plunger within said fuse-case; a rotatable protecting-sleeve connected with said plunger by a quick screw-thread connection; and releasable means for locking said plunger and sleeve in extended and safe position.

18. A fuse for explosive projectiles comprising a fuse-case; a percussion member; a non-rotatable longitudinally-movable detonating-plunger within said fuse-case; a rotatable protecting-sleeve connected with said plunger by a quick screw-thread connection, and releasable means, sensitive to thermic action, for locking said plunger and hood in extended and safe position.

19. A fuse for explosive projectiles comprising a fuse-case; a percussion member; a non-rotatable longitudinally-movable detonating-plunger having a screw-threaded firing-pin; a rotatable protecting-sleeve mounted on said

screw-threaded firing-pin; and releasable means for locking said plunger and sleeve normally in extended and safe position.

20. A fuse for explosive projectiles comprising a fuse-case; a percussion member; a non-rotatable longitudinally-movable detonating-plunger having a screw-threaded firing-pin; a rotatable protecting-sleeve mounted on said screw-threaded firing-pin, and releasable means, sensitive to thermic action, for locking said plunger and sleeve normally in extended and safe position.

21. A fuse for explosive projectiles comprising a fuse-case, a percussion member, a detonating-plunger, and an annular metallic locking device for said plunger, said locking device being sensitive to thermic action and adapted to release said plunger upon firing of the projectile.

22. A fuse for explosive projectiles comprising a fuse-case, a percussion member, a detonating-plunger and a locking device for said plunger comprising a divided thermostatic annular strip composed of two substances differently expansible by heat, said strip being adapted to release said plunger upon firing of the projectile.

23. A locking device, for safety-fuses, consisting of a divided thermostatic annular strip composed of a plurality of substances having different coefficients of expansion by heat, and having radial locking projections, combined with a detonating-plunger adapted to be engaged by said projections when in locked position.

In testimony whereof I affix my signature in presence of two witnesses.

DAVID J. CARTWRIGHT.
